(57) **CLAIM**

The ornamental design for a tool stand, as shown and described.

DESCRIPTION

FIG. 1 is a perspective view of a tool stand showing my new design;

FIG. 2 is a front view thereof;

FIG. 3 is a back view thereof;

FIG. 4 is a side view thereof, the opposite side being a mirror image thereof;

FIG. 5 is a top side view thereof;

FIG. 6 is a bottom side view thereof;

FIG. 7 is a perspective view showing the tool stand in a position of use; and,

FIG. 8 is a side view of the tool stand shown in a position in use.

The purpose of broken lines in the drawings is for environment in which the article embodying the design is used. The broken lines form no part of the claimed design or of an embodiment thereof.
